UNITED STATES PATENT OFFICE.

JAMES CHRISTOPHER HALLIGAN, OF BRISBANE, QUEENSLAND, ASSIGNOR
OF ONE-HALF TO JAMES FERGUSON, OF SAME PLACE.

LITHOGRAPHIC MACHINE.

SPECIFICATION forming part of Letters Patent No. 633,958, dated September 26, 1899.

Application filed February 10, 1899. Serial No. 706,166. (No model.)

To all whom it may concern:

Be it known that I, JAMES CHRISTOPHER HALLIGAN, a subject of the Queen of Great Britain and Ireland, and a resident of 75 Queen street, Brisbane, in the Colony of Queensland, have invented certain new and useful Improvements in Lithographic Machines, (for which I have applied for patents in Queensland September 1, 1898, No. 4,549; 10 in New South Wales September 6, 1898, No. 8,631; in Victoria September 6, 1898, No. 15,514, and in Great Britain October 5, 1898, No. 20,988,) of which the following is a specification.

15 My invention relates to improvements in lithographic machines, and has special reference to a means for arresting the movement of the printing-roller at the same place on each strike of the machine and to prevent 20 breakage of the dampening-rollers or lifter, this invention being a further improvement upon my previous invention, application for which was filed April 15, 1898, Serial No. 677,705.

25 The object of my invention is the provision of an attachment for the purpose set forth which is the embodiment of simplicity, durability, and cheapness, thus producing a very useful and practical device.

30 To attain the desired objects, the invention consists of an improvement for lithographic machines embodying novel features of construction and combination of parts, substantially as disclosed herein.

35 Figure 1 is a side view of a portion of a lithographic machine with my attachment or improvement placed thereon; and Fig. 2 is a front elevation of the pressure-cylinder, with my invention for arresting the movement 40 thereof attached.

In the drawings, A designates a cam upon the main crank-shaft of a lithographic machine, and said cam is adapted to be revolved in the rectangular frame B, carried by the 45 slidably-mounted pressure-rod C, secured upon the side of the machine.

Carried in the brass D upon the end of the pressure-rod and slideable in the stationary jaws E is the pressure-cylinder F, which has 50 secured upon one of its ends the metal circu-

lar disk G, provided with a semicircular notch H in its periphery and a stud J upon the outer face.

Secured to the top of the machine is the spring tension bracket or arm K, carrying the 55 revolving friction-roller L, which is adapted to impinge the periphery of the disk and engage the notch H to arrest the movement of the disk, and consequently the pressure-cylinder, and to return the cylinder and disk 60 quickly after it has nearly completed a revolution and to arrest it while there I employ the tension-spring M, which is connected to the machine by means of the bracket N and to the stud J of the disk. Thus it will be seen that 65 when the pressure-cylinder is revolved in the ordinary manner the slidably-mounted pressure-rod moves the roller up and down and the spring allows the roller to be revolved slowly until it has passed the point where the tension 70 is at its greatest, when the spring quickly revolves the roller and brings the disk into contact with the friction-roller, where it is arrested by the curved notch and spring also.

Formed upon the inner side of the pressure-rod is a lug or stud O, against which is adapted to abut the end of the lever P, which is pivoted to the jaws E at P', and to the other end of this lever is movably connected the damper-lifter or vertically-movable rod Q, 80 whose lower end slides in an opening in the side frame R of the machine, and this lever is so operated as when the pressure-rod descends that the damper lifter or rod ascends, and thus raises the bracket S, carried by the 85 rod, and consequently the dampening-rollers T, carried by the bracket and upon the upper end of the lifter.

From this description the operation of my invention is readily understood, but, briefly 90 stated, it is as follows: The machine is set in motion and the cam raises the pressure-rod, which causes the cylinder to rise and the dampening-rollers to descend, and when the pressure-rod descends the dampening-rollers 95 ascend; but while the dampening-rollers are descending the disk, with its friction-roller and tension-spring, is arrested, and thus the sudden fall of the rollers is broken or stopped.

Thus it will be seen that I produce a very 100

simple, durable, and inexpensive improvement in lithographic machines which is very useful and practical.

I claim—

- 5 1. In combination with a lithographic machine, of a pressure-rod carrying a pressure-cylinder, a disk carried by said cylinder, means to contact with said disk and arrest the movement thereof, a lifter operated by said pressure-rod and adapted to be arrested simultaneously with the cylinder and dampening-rollers carried by said lifter.
- 10 2. In combination with a lithographic machine, of a slidingly-mounted pressure-rod adapted to be operated by the crank-shaft of the machine, a pressure-cylinder carried by said rod, a disk carried upon one end of the cylinder and provided with a notch and a stud, means for contacting with the periphery of the disk and entering the notch to arrest the movement of the cylinder, a lever pivoted to the machine and adapted to be contacted with by the pressure-rod, a vertically-movable roller lifter or rod connected to the other end 25 of the lever, and roller-holders carried at the upper end of said lifter or rod.
- 25 3. In combination with a lithographic ma-

chine, of a pressure-rod carrying a cylinder, a disk carried by the cylinder and provided with a notch in its periphery, a spring-arm 30 carrying a friction-roller and adapted to impinge upon the periphery of the disk and force the roller into engagement with said notch, and a spring to arrest the cylinder and also to return the same to be arrested by the spring-arm carrying the friction-roller connected to the disk and the machine.

4. In combination with a lithographic machine, of a pressure-rod slidably connected to said machine, a pressure-cylinder carried by 40 said rod, a disk having a stud and a notch connected to one end of the cylinder, means for contacting with or engaging said notch and stud to arrest the movement of the cylinder, a lifter movably connected with the 45 machine and pressure-rod, and adapted to ascend as the pressure-rod descends and vice versa and dampening-rollers carried by said lifter.

JAMES CHRISTOPHER HALIGAN.
